Attorney

UNITED STATES PATENT OFFICE.

EDWIN F. LAWRENCE, OF STERLING, ILLINOIS, ASSIGNOR OF ONE-HALF
TO JOHN H. LAWRENCE, OF STERLING, ILLINOIS.

DOOR-HANGER.

SPECIFICATION forming part of Letters Patent No. 713,115, dated November 11, 1902.

Application filed August 11, 1902. Serial No. 119,199. (No model.)

To all whom it may concern:

Be it known that I, EDWIN F. LAWRENCE, a citizen of the United States of America, and a resident of Sterling, in the county of White-
5 side and State of Illinois, have invented cer-
tain new and useful Improvements in Door-
Hangers, of which the following is a specifi-
cation.

The present invention relates to the single-
10 track type of door-hangers, and has for its ob-
ject to provide a simple, strong, and durable
arrangement of parts which will permit of the
door being swung outward away from the
doorway at its lower end for ventilating and
15 other like purposes, all as will hereinafter
more fully appear, and be more particularly
pointed out in the claim.

In the accompanying drawings, illustrative
20 of the present invention, Figure 1 is an end
elevation of a door-hanger embodying the
present invention; Fig. 2, a rear elevation of
the same; Figs. 3 and 4, fragmentary trans-
verse sectional elevations of modified forms
25 of the pivot-eyes on the bearing-plate of the
hanger-frame.

Similar numerals of reference indicate like
parts in the several views.

Referring to the drawings, 1 represents the
longitudinal track member secured in a hori-
30 zontal position to the wall of the building or
other structure by attaching brackets 2 to at-
tain a separated relation between the wall and
the track.

3 is the track roller or pulley, formed with
35 the usual grooved periphery to fit the track-
rail and provided with the usual lateral trun-
nions or journal-pins 4, by means of which it
is journaled in the upper end of the hanger-
frame.

40 5 is an inverted-U-shaped plate constitut-
ing the part of the hanger in which the trun-
nion-pins 4 of the track-roller 3 have bearing
in any usual and well-known manner.

6 is a pendent hook-shaped extension on
45 the pulley-frame 5, adapted to engage under
the track member 1 to prevent independent
side movement of such pulley-frame with re-
lation to such track member.

7 is a pendent strap, of which there may be
50 one or more to each individual hanger, the
lower end of which is adapted for substantial
attachment to the door and the upper end of
which is hook shape, so as to engage over and
have bearing upon the crown of the pulley-

frame to afford a substantial support to the 55
door.

The construction so far described is usual
and common to door-hangers now in general
use, and the novelty of the present invention
consists in a particular construction and ar- 60
rangement of parts, as follows:

8 represents pivot-eyes formed or secured
upon the rear face of the pulley-frame 5 at
points adjacent to the crown thereof.

9 represents companion pivot-eyes formed 65
at the free and rear end of the hook-shaped
upper portion of the hanger-strap 7, the ar-
rangement being such that such eyes may be
pivotally connected together by a horizontal
pintle or rod 10. 70

With the present improved construction
the door is very substantially supported in a
manner entirely independent of and without
any strain upon the pintle-rod 10, in that all
the downward stress of the door is wholly 75
taken by the hook-shaped upper end of the
hanger-strap 7. The only time that any strain
is upon the pintle-pin 10 is when the door is
tilted so as to be open along its bottom, in
which condition the hanger parts will assume 80
the position indicated in dotted lines in Fig. 1.

In the practical manufacture of the present
invention the pivot-eyes 8 of the pulley-frame
5 may be made as separate parts and be riv-
eted in place, as indicated in Figs. 1 and 2, or 85
they may be integrally formed in said frame,
as indicated in Figs. 3 and 4.

Having thus fully described my said invention,
what I claim as new, and desire to se-
cure by Letters Patent, is— 90

The combination in a door-hanger, of a pul-
ley-frame having an inverted-U form, a track-
pulley journal in the same, a hanger-strap
provided with a hook-shaped upper end en-
gaging over the crown of the pulley-frame 95
aforesaid, and means for pivotally connect-
ing the hanger-strap and the pulley-frame
together the same comprising pivot-eyes ar-
ranged on the back of the pulley-frame, com-
panion pivot-eyes on the free end of the 100
hanger-strap, and a pivot-pintle connecting
said eyes together, substantially as set forth.

Signed at Chicago, Illinois, this 4th day of
August, 1902.

EDWIN F. LAWRENCE.
